UNITED STATES PATENT OFFICE.

THOMAS V. TUCKER, OF HENDERSON, IOWA.

CAR-COUPING.

SPECIFICATION forming part of Letters Patent No. 259,246, dated June 6, 1882.

Application filed March 17, 1882. (No model.)

To all whom it may concern:

Be it known that I, THOMAS V. TUCKER, of Henderson, in the county of Mills and State of Iowa, have invented a new and useful Improvement in Car-Couplings, of which the following is a full, clear, and exact description.

My invention consists in a novel construction and combination, with a draw-head, of a vertical sleeve in which the coupling-pin works, a sliding spring-latch for holding up the pin, a lever and connections for raising the pin from either the top or the side of the car, and a link provided with lateral projections for engagement with the sliding spring-catch to release the pin, and certain details herein-after more particularly described.

Reference is to be had to the accompanying drawings, forming part of this specification, in which similar letters of reference indicate corresponding parts in all the figures.

Figure 1 is a perspective view of my invention as applied to a car. Fig. 2 is a perspective view of a modification. Figs. 3, 4, 5, and 6 are detail views.

The draw-head A is made with its mouth flaring in the usual manner. The top and bottom B B² project laterally at the front, and through the projecting portions pass pins b, which may be used in connection with side coupling-links when desired. From the top B rises a vertical sleeve, D, in which the coupling-pin C works, surrounded by a spiral spring, c. (Shown in dotted lines.) In the sleeve D is a longitudinal slot, d, through which projects an arm, e, extending laterally from the pin. To this arm is attached one end of a chain, f, the other end of which is attached to a lug or eye on a bar, G, arranged to slide vertically against the end wall of the car. The bar G is held in place by a keeper, H, behind which is a pressure-spring, J. The upper end of the bar G extends to the top of the car, and is provided with a handle, g. Near the bottom of the car the bar G is bent at a right angle, so as to form a horizontal arm, G², which extends to the side of the car, and is provided with a handle, g², and it is held in place by a keeper, K. Near the lower portion or angle of the bar G is an inclined plane, terminating abruptly in a shoulder, i.

Fig. 3 represents a device for holding the coupling-pin up and in position for coupling and uncoupling. It consists of a plate, L, bent at a right angle, so as to form a vertical side and a horizontal side, which latter terminates in a lip, l, large enough to obstruct the upper hole in the mouth of the draw-head, through which the coupling-pin passes. From the rear edge of the vertical portion of the plate extends a shank or stem, M, surrounded by a spiral spring, m. The plate thus formed is attached to the draw-head, so that the vertical portion works outside of the draw-head and the horizontal portion works in a recess in the top of the mouth. The rear end of the shank M works in a staple or keeper, n, and a pin or bolt, p, passes through a slot, s, in the plate and into the side of the draw-head, and the sliding latch thus formed is held in place and allowed to slide back and forth, the spring m having a tendency to keep it pushed toward the front of the draw-head. The front edge of the vertical side of the latch is braced and strengthened by a bar, l².

The link R is used in connection with this coupling, and is provided with two arms, r r, projecting laterally from its sides in opposite directions, as shown in Fig. 4.

The operation is as follows: The bar G is raised until the shoulder i engages with the keeper H, where it is held by the pressure of the spring J. The length of the chain f is such that when the bar G reaches the height referred to the pin C is high enough to allow the lip l of the latch L to spring under a shoulder on the pin and hold it in the position shown in Fig. 1. The bar G may then be lowered to its original position by disengaging the shoulder i from the keeper H without interfering with the position of the pin. When a car approaches to be coupled the draw-head of the approaching car strikes the bar l² and forces back the latch L, so as to release the pin C and allow its spring c to force it down and hold it in engagement with the link R.

It will be seen that the bar G may be operated either from the top of the car by means of the handle g or from the side of the car by means of the handle g².

If desired, the arm G² may have a lever sub-

stituted for it and pivoted to the lower end of the bar.

In Fig. 2 is shown a modification which may be used on a platform-car, if desired. The bar 5 G and chain f are dispensed with and the pin C is held up by means of a lug or stud, c³, on the pin engaging with a notch or shoulder, d², in the slot d of the sleeve D, the upper end of the pin being provided with a handle, c², for 10 operating it. The link V (shown in Figs. 5 and 6) is used in connection with both draw-heads. It is provided with projections v on its under side for the purpose of holding it level in the mouth of the draw-head when used in the position shown in Fig. 5. By reversing it, as 15 shown in Fig. 6, it is allowed to hang down so as to couple with a lower car.

The advantages of this invention are: The pin is held securely when raised by the lip l 20 of the latch L, and when the pin is down it is held firmly and prevented from bouncing up by means of the spring e surrounding it. By leaving the bar G in its raised position the pin is held up and prevented from falling in case 25 of the latch L being struck by accident, and by lowering the bar G, the pin is free to fall when the latch is forced back.

Any ordinary link may be used with this draw-head, and the coupling accomplished by 30 allowing the draw-head of the approaching car to strike the latch L and force it back. The link R is employed at the front of an engine, in which case the arm r will strike the latch L. When the link V is used the approaching draw-head strikes the latch. 35

If desired, the bolts b (shown in Figs. 1 and 2) may be used in connection with links of the ordinary description.

Having thus fully described my invention, I claim as new and desire to secure by Letters 40 Patent—

1. In a car-coupling, the combination, with the draw-head A and the sleeve D, provided with the longitudinal slot d, of the coupling-pin provided with the laterally-projecting arm 45 e and the spring e, surrounding the said pin, substantially as and for the purpose set forth.

2. The combination, with the coupling-pin C, provided with the arm e and chain f, of the arm G, provided with the shoulder i and horizontal arm G², the keeper H, and the pressure-spring J, substantially as and for the purpose 50 herein described.

3. The latch L, provided with the horizontal lip l, shank M, and spring m, in combination 55 with the draw-head A and coupling-pin C, substantially as and for the purpose described.

4. The link R, provided with lateral arms r r, in combination with the draw-head A and latch L, substantially as and for the purpose 60 herein described.

5. The combination of a sleeve, D, provided with a slot, d, and lateral shoulder d², and a pin, C, provided with a lug or stud, c³, as shown and described, for the purpose specified.

THOMAS V. TUCKER.
